CLAIM

The ornamental design for the portable insulated jug, as shown and described.

DESCRIPTION

FIG. 1 is perspective view of the portable insulated jug; FIG. 2 is a front elevation view of the portable insulated jug; FIG. 3 is a rear elevation view of the portable insulated jug; FIG. 4 is a left elevation view of the portable insulated jug; FIG. 5 is a right elevation view of the portable insulated jug; FIG. 6 is a bottom view of the portable insulated jug; and, FIG. 7 is a top view of the portable insulated jug. The long dash, short dash broken line shown in FIG. 6 depict a boundary line and the broken lines and area within form no part of the claimed design. The remaining broken lines shown in FIG. 6 depict portions of the portable insulated jug that form no part of the claimed design.

1 Claim, 6 Drawing Sheets
